(57) **CLAIM**

The ornamental design for air flow conditioner, as shown.

DESCRIPTION

FIG. 1 is a rear isometric view of the invention in the preferred embodiment showing the two rectangular air flow openings covered by semi-rigid material cloth, linked to the perimeter edge of the air flow openings.

FIG. 2 is a front isometric view of the invention shown in FIG. 1 showing the two fans and the control buttons.

FIG. 3 is a top view of the invention.

FIG. 4 is a front view.

FIG. 5 is a rear view.

FIG. 6 is a bottom view.

FIG. 7 is a right side view; and,

FIG. 8 is left side view.
